MEANS FOR CEMENTING BETWEEN
MULTIPLE SANDSAlexander Boynton, San Antonio, Tex.; Sida S.
Martin executrix of said Alexander Boynton,
deceased

Application October 14, 1941, Serial No. 414,956

4 Claims. (Cl. 166—1)

My invention relates to means for cementing between multiple sands of oil and gas wells.

The principal object is to provide new and simple means for cementing between and above the several producing formations of a well.

Another object is to enable the operator to determine, with great accuracy, the exact places where cement will be left in the well.

In carrying out the cementing between separate sands, I employ a special tool attached to the lower end of the drill stem or tubing. This tool has two expansible members adapted to be expanded by pump pressure and I perforate the nipple between these expansible members, so that cement pumped downward through the drill pipe will be forced out through openings in the casing, each of these openings being governed by a yieldable valve normally held closed by the pressure of drilling mud around the casing and which valves are adapted to be opened by pump pressure transmitted through the drill stem. A removable valve, which may be dropped through the drill stem, is adapted to close the opening through the lower end of the special cementing tool and another removable valve, which is of such specific gravity that it will float on cement and will sink in the drilling mud, is employed to stall the pumps each time the proper amount of cement has been discharged through the tool, in order to accomplish the several cementing operations. In this connection, I employ another special tool for recovering the aforementioned valves whenever the cementing tool should be raised to another place where cement is to be discharged through the casing, or where mud or water is to be pumped through it in order to force surplus cement out of the well.

To prevent cement from penetrating the producing formations, I first wash clean the exposed surfaces of these formations, after which operations I introduce liquid cement into the well bore surrounding the casing, the cement being charged with valve-like sand sealing substances which are adapted to adhere to the sticky film and which will cover and close all openings in the producing formation; thus insulating it from penetration by the cement, all of which will become clear from an examination of the following specification and the accompanying drawing, in which—

Fig. 1 is a vertical section through the well casing and valve assemblies, also showing the surrounding earth formations.

Fig. 2 is a longitudinal section through the cementing tool.

Fig. 3 is a cross section on the line 3—3, Fig. 2.

Fig. 4 is a cross section on the line 4—4, Fig. 2.
Fig. 5 is an outside view of the wire shields.

Fig. 6 is a frontal elevation of the check valve spring.

Fig. 7 is a vertical section through a portion of one of the valve assemblies, the screws and valve being shown uncut.

Method

In order to prevent the aforesigned harmful effects of drilling mud upon the producing sands, I employ (1) clean water to wash the sand before cementing the well. (2) Then I fill the annular space between casing and sand with heavy mud charged with sand sealing substances, and (3) after the preceding operations, I apply cement slurry charged with similar sand sealing substances adapted to form miniature valves which will be forced to close all pores in the sand by pressure of the cement which thus will be excluded from sealing the sand against subsequent flow of production into the well. A small portion of the cement will contact the sand for only a few minutes during the cementing operation, the sand sealing substances in the cement being precautionary during these few minutes.

The first of said operations is accomplished by pumping a few barrels of clear water rapidly ahead of the heavy mud.

30 The second operation consists of following the wash water with enough sand seal charged heavy mud to cover the sand and support the cement above it.

35 The third operation is to place the cementing tool above the sand and pump in cement slurry, thoroughly charged with mica flakes and ground rubber, the latter varying from dust to particles somewhat larger than the largest pores of the sand which is being protected from intrusion of the cement.

40 The finer particles of the rubber being more numerous than the flakes of mica, will be drawn out of the cement slurry and will close the small pores in the sand. Larger particles of the rubber will be drawn into the larger pores and the mica flakes will be forced over all pores which the ground rubber failed to close. Of course, some of the mica flakes will be preceded by the particles of rubber in contacting the pores of the sand.

45 60 Under such circumstances, the rubber particles will reinforce the mica in stopping all remaining leaks out through the sand.

It is preferable to mix a larger proportion of ground rubber in the first one-fourth of the cement than in the remainder thereof. The pro-

portion of mica flakes may be the same throughout.

Satisfactory results ordinarily will be obtained by employing a mixture of two to five per cent ground rubber and five to ten per cent mica flakes, the rubber content being increased ten to fifteen per cent in the first one-fourth of the slurry, it being understood that these proportions relate to volume and are subject to wide variations.

The cement will set within a few hours after being pumped into the well. The particles of rubber will be dissolved soon thereafter by the hydrocarbons. The mica flakes, being larger than the pores of the sand, will flow out of the well with the first production. The original interstices of the producing sand thus are left unobstructed by the one-way valves of ground rubber and mica flakes which stand on guard over the sand during the time of danger to its and leave thereafter.

The means

In Fig. 2, illustrating the cementing tool, the upper and lower expandable members 2, which may be of rubber, are received closely over the mandrel 1 which may be a steel casting having the discharge openings 1c formed between its retainer cups 1a. The upper and lower expandable members 2, which are adapted to be expanded by pressure acting upon their inner surfaces from within the mandrel 1 via the lateral openings 1b, have their proximate tapered ends closely received within the retainer cup 1a of the mandrel 1. These expandable members have their extreme tapered ends received closely within the retainer cups 5, threadedly engaged over the mandrel, where they may be secured in proper position by the locking sleeve 6, and the swaged nipple 7, both of which latter members also have threaded engagement over the mandrel 1. The wires 3, which may be of spring steel, are received closely within the longitudinal slots 2a of the members 2 (see Fig. 4), and have their ends slideable within the grooves 4a of the wire shields 4, these shields being received closely within the retainer cups 1a and 5 and being imbedded partially within the exterior surfaces of the expandable members 2, proximate their ends.

The cylindrical tapered ends of the expandable members 2 form hermetic contact with the retainer cups 1a and 5 whenever the members 2 are expanded against the well casing 17 (see Fig. 1) by pressure from within them and while so expanded the wires 3 protect the expandable members from being abraded unduly by the casing as the cementing tool is raised or lowered. The shields 4 provide that the ends of the wires are free and that the expandable members can never become impinged upon them to thereby impair their movements in yielding to the pressure which expands the members 2.

The swaged nipple 7, secured upon the lower end of the mandrel 1, has its lower portion of reduced diameter adapted to receive the shell 14 with such as $\frac{1}{8}$ " clearance all around it. This shell, having the depending central extension 14b somewhat smaller than the restricted opening 7b through the nipple 7, has formed upon it the valve 14c adapted to engage the seat 7a formed within the nipple 7.

The connection member 8, having the restricted circular axial opening 8b somewhat larger than the external diameter of the shell 14, has threaded connection with the mandrel 1 and with the tool joint 9 which, in turn, has similar connection with the drill pipe 10.

The shell 11, shown to be identical with the other shell 14, has the axially depending rod 11a over which the washers or float units 12 may be received closely. The lower member of these washers is formed into the valve 12a adapted to become engaged upon the seat 8a formed within the connection member 8. These washers and the valve member, being of slightly larger diameter than that of the shell 11 and having small clearance within the tool joint 9, are secured upon the depending rod 11a by the nut 13. The shell 11 and the other members assembled upon it will be referred to as the float valve assembly and the valve seat 8a as the float valve seat. The washers 12 and the valve 12a may be of hardened rubber, gutta percha or the like, and the float valve assembly should be of such specific gravity that it will float upon the cement slurry used to cement the well and that it will sink in the mud fluid employed to force the cement down through the drill pipe or tubing. Several of the washers or float units 12 are employed in order that the float valve assembly may be made to have the correct specific gravity.

The shell 11 and its extension 11a being metallic and, consequently, being of greater specific gravity than that of the cement slurry, and the washers or float units 12 being of less specific gravity than that of the mud slurry, it is evident that the specific gravity of the assembly can be decreased by adding washers, or that its specific gravity may be increased by decreasing the number of these washers.

The float valve assembly designated generally by the numeral 11, and the shell 14 upon the valve 14c are adapted to pass through the drill pipe 10 and the tool joints therein and to engage upon their respective seats in a manner that will be explained.

The shell 14 has the intruding pins 16 secured upon it by means of the welds 16a. The shell 11 has the intruding pins 15 secured upon it by the welds 15a. A suitable fishing out or catching and releasing tool, such as is set out in my Patent #2,250,463, issued July 29, 1941 may be employed to fetch out the float valve assembly and the shell 14, the lateral openings 11b of the shell 11 and the similar openings 14a of the shell 14 being provided that the fishing tool may force mud or cement slurry out of the shells.

In Fig. 7, which illustrates the simple valve mechanism employed in the well casing in conjunction with the cementing tool shown in Fig. 2, the nipple 21, adapted to be joined threadedly into the well casing 17, has the lateral openings 21a, each having its outer portion expanded into the valve seat 21b which is engaged normally by the valve 18 having the short shank 18a which may be secured within the central opening 18b of the flat spring 19 by the weld 18b. Proximate its ends, this spring has the slots 19a within which the smooth shanks 20a of the screws 20 have slight clearance. These screws are secured within the nipple 21 at such distance apart that the proximate ends of the slots 19a are in close proximity to the screws, in order to maintain the valve 18 in position at all times to re-engage its seat after being disengaged therefrom. The slots 19a extend somewhat beyond the screws, in order that the spring will be permitted to contract slightly as the valve is forced open, it being understood that the spring is installed so as to transmit seating force to the valve.

The discharge nipple 22, being adapted to be joined into the casing string, has the protecting

shell 22a housing the spring and valve and has such clearance with them as to allow the valve to be opened.

It is apparent that the valve 18 may be dispensed with if the nipple 21 be provided with a smooth flat external surface adapted to engage the spring itself, which thus can be converted into a valve at its place of engagement over the opening 21a.

A plurality of such valves as the one illustrated in Fig. 7 may be installed upon each of the nipples 21, as appears in Fig. 1. The valves so installed operate as check valves which permit fluid from within the casing to be forced by them, but prevent fluid from the annular space surrounding the casing from entering the casing. The assembly of valves upon each nipple 21 will be referred to as the valve assembly.

In Fig. 1, the well casing 17 is shown positioned centrally within the well bore 17a, the valve assemblies 42, 43, 44, 45, and 46 being positioned so as to provide that the annular space surrounding the casing may be filled with cement slurry in such manner as to protect each of the producing formations, as will be explained. Such formations will be referred to as "sands."

The casing shoe 23, connected upon the lower end of the casing, has within it the concrete 24 having the central opening 24a and having its lower end formed into the valve seat 24b normally engaged by the valve 25 secured upon the rod 26. The coiled spring 27, having slight clearance within the shoe 23, engages under the spider 28, which is joined to the rod upon which it is secured by the nut 29. This concrete and the valve assembly installed upon it are adapted to be drilled out upon completion of the well and provide, in the meantime, that fluid within the well bore exterior of the casing will be excluded from the casing while, at the same time, fluid may be pumped through the casing.

It being understood that the cement slurry may be charged with ingredients such as have been previously mentioned in this specification, it will be understood further that the sands 30, 34, and 38 are productive and, consequently, that the annular spaces 31, 35, and 39 are to be left free of cement while the cement is setting between the sands. The formations 32, 36, and 40 being unproductive and apt to carry water or unwanted gas, are to have their respective adjacent annular spaces filled with the cement 33, 37, and 41, while heavy sand seal treated mud in the annular spaces 31, 35, and 39 support the cement above them.

Operation

Just before cementing the well, enough heavy and seal treated mud will be pumped through the casing to fill the annular space 31 between the casing and the productive formation 30. This mud should be as nearly as possible of the same specific gravity as that of the cement slurry in order to prevent the cement about to be placed opposite the non-productive formation 32 from settling out.

In cementing off the non-productive formation according to the plan stated in the preceding paragraph, the cementing tool illustrated in Fig. 2 will be attached to the drill stem or tubing and lowered to the position where the expandable members 2 will be one above and the other below the valve assembly 46, it being understood that the valves 12a and 14c are not employed as yet.

- The valve 14c now will be dropped through the drill stem or pumped down. When it engages the seat 1a, the expandable members 2 will be expanded by the pump pressure and will engage the well casing 17. The pump will stall, unless the expandable members are on either side of the lateral openings 21a through the nipple 21 of the valve assembly 46. If the pump stalls, raise or lower the drill stem until the pump starts. 10 Then proceed as follows: (1) Pump a few barrels of clear water through the drill stem in order to wash clean the exposed surface of the non-productive formation 32. The water will pass out of the drill stem and into the annular space between the casing and the well bore 17a via the slots 1c of the member 1, the lateral openings 21a of the nipple 21 (opening the check valve 18) and the annular space between the nipple 21 and the shell 22a. This path will be followed, of course, by all pump fluid forced through the cementing tool. (2) Pump into the drill stem enough sand seal charged cement slurry to fill the annular space between the non-productive formation 32 and the casing. (3) Place the float valve assembly 11 on top of the cement and pump down the cement until the pump stalls. The valve 12a will be engaged then upon the float valve seat 8a, as shown in Fig. 2. (4) Remove the float valve assembly 11 and the valve 14c by means of a special tool such as was previously mentioned, these members being removed in order that pressure may equalize on both sides of the expandable members when the drill stem is raised. (5) Raise the drill stem until the cementing tool has its expandable members 2 positioned on either side of the valve assembly 45. This position of the expandable members can be tested again by the pump after the valve 14c has been dropped, as was explained in connection with the make-ready for pumping cement through the valve assembly 46. (6) Again drop the valve 14c into the drill stem and pump into the drill stem enough heavy sand seal charged mud to remove any surplus cement from the exposed surface of the sand 34. (7) Remove the valve 14c and raise the cementing tool to the position opposite the valve assembly 44. 30 40 45 50 55
- The formations 36 and 40 may be cemented in the same manner as was specified for cementing the formation 32; thereby placing the cement where indicated at 3, 37, and 41; while the spaces 31, 35, and 39 are left clean of cement, but charged with sand seal laden heavy mud, as stated. 60
- It is apparent that all fluid pumped through the valve assemblies will be held by them outside of the casing while the cement sets. Another important feature of this cementing means is that the tendency of cement slurry to settle before it sets is retarded very much by the enlarged shells 22a of the nipples 22 if the mud employed to fill the annular space below the cement should be much lighter than the cement. 65
- After the cement sets, the casing may be perforated opposite the several sands by employing any one of several tools for the purpose which are adapted to be operated by the drill stem. Gun perforations, being intended primarily to penetrate through the cement which heretofore was left in the sands and between them and the casing, need not be employed in wells cemented by this means, because with this practice no impervious substances are left between the casing 70 75

and the productive formations and no cement is permitted to penetrate the sands.

I claim:

1. In a means for cementing casing in well bores, a float valve assembly comprising: a shell; a depending rod thereon; a valve on said rod; float units upon said rod and between said valve and shell, said units being of proper specific gravity to cause said assembly to sink in mud fluid and float on cement slurry; and means on said shell for being engaged by a fishing-out tool.

2. A cementing tool for use in cementing a casing in place in a well extending through multiple sands, said tool comprising: a tubular mandrel formed with discharge openings intermediate its extremities; expansible means on each side of said openings for establishing a seal between said mandrel and casing; a drill pipe; a connecting member secured to the upper end of said mandrel and having a passage provided with a valve seat of a lesser diameter than the internal diameter of the drill pipe; a joinder means between said drill pipe and said connecting member and having a passage of a greater diameter than the diameter of the valve seat in said connecting member; a nipple secured to

the lower end of said mandrel and having an elongated portion terminating in an outlet having a valve seat of less diameter than the internal diameter of the elongated portion of the nipple; a float valve assembly located in said connecting member and said joinder means and comprising a shell having a depending rod, float washers and a valve positioned on said rod, said assembly being arranged to be dropped from the surface through the drill pipe to seat on the valve seat of said connecting member; and a valve having a shell and a depending extension and being constructed to be dropped, before said float valve assembly, through said drill pipe, said joinder means and said connecting member into said nipple to seat on the valve seat of said nipple, said last named depending extension, when the valve is seated, projecting out beyond the outer end of said nipple.

20 3. The tool of claim 2 wherein the shells are perforated.

4. The tool of claim 2 wherein the shells have inwardly projecting pins for engagement by a suitable fishing-out tool.

ALEXANDER BOYNTON.
